DESIGN FOR A HAND TRUCK

Jesse G. Eagleson, Johnson County, Kans., assignor to The Garden Shop, Inc., Kansas City, Mo., a corporation of Missouri

Application February 28, 1938, Serial No. 75,452

Term of patent 14 years

To all whom it may concern:

Be it known that I, Jesse G. Eagleson, a resident of Johnson County, State of Kansas, have invented a new, original, and ornamental Design for a Hand Truck, of which the following is a specification, reference being had to the accompanying drawing, forming part thereof, in which

Fig. 1 is a side perspective view of a hand truck showing my new design.

Fig. 2 is a top perspective view of the hand truck shown in Fig. 1.

Fig. 3 is a side elevation of the hand truck shown in Fig. 1.

I claim:

The ornamental design for a hand truck substantially as shown.

JESSE G. EAGLESON.
